UNITED STATES PATENT OFFICE.

HENRY S. LATHROP, OF SAN FRANCISCO, CALIFORNIA.

DEPTH AND INCLINATION INDICATOR AND RECORDER.

SPECIFICATION forming part of Letters Patent No. 715,095, dated December 2, 1902.

Application filed June 15, 1901. Serial No. 64,750. (No model.)

To all whom it may concern:

Be it known that I, HENRY S. LATHROP, a citizen of the United States, residing at San Francisco, in the county of San Francisco and State of California, have invented certain new and useful Improvements in a Depth-Gage, Inclinometer, and Automatic Balance for Submarine Boats, of which the following is a specification.

10 My invention relates to an improved device for automatically recording the inclination of a submarine boat and also for automatically recording the depth to which the boat is submerged.

15 My invention therefore resides in the novel construction, combination, and arrangement of parts for the above ends, hereinafter fully specified, and particularly pointed out in the claims.

20 In the accompanying drawings, Figure 1 is a diagrammatic view of a submarine boat equipped with my recording device. Fig. 2 is an enlarged front elevation of the recording device, parts being shown in vertical section. Fig. 3 is a plan view of the same, broken away in part. Fig. 4 is a broken horizontal section of one end of the boat. Fig. 5 is a central section of the pressure-transmitting device. Fig. 6 is a horizontal section on the 25 line A A of Fig. 2.

Referring to the drawings, 1 represents the shell of a submarine boat, and 2 represents the lookout thereof.

30 3 are narrow tubes leading from the side of the boat at the bow and stern, respectively, to pressure-transmitting devices 4, located at the bow and stern. Each of said devices 4 comprises two diaphragms 5 and 6, differing in area, the larger diaphragm 5 being open to 35 the pressure of the surrounding water through the tube 3 and the smaller diaphragm 6 transmitting pressure to a narrow tube 7. Said diaphragms 5 and 6 are suitably held in a casing 8 and with said casing 8 form two pressure-chambers, which are connected by a pipe 9, provided with a cock 10 for opening and closing the passage through said pipe.

The narrow tubes 7 lead from the pressure-transmitting devices at the bow and stern of the boat to a central point below the lookout and are there connected to a depth-gage and inclinometer, (shown at 11.) Said latter appa-

ratus is mounted upon a board 12. Secured to said board by brackets 13 are a pair of cylindrical guides 14, to the lower ends of which are attached the ends of the tubes 7. In said guides 14 slide cup-shaped pistons 15, said pistons being suitably packed within the guides 14 to prevent the escape of the water under pressure. To said pistons 15 are attached rods 16, which slide vertically in guides 17 18, fixedly secured upon the board 12, and said rods are provided with pins 19, which engage slots 20 in a pointer 21, pivoted at 22 upon a frame 23. The pins 19 are adjustable 65 upon the rods 16 by means of set-screws 24. The frame 23 comprises upper and lower side bars 25, connected by a cross-bar 26, to which the pointer 21 is pivotally attached, and side bars 25 extend divergently, their outer ends 70 being connected by an arc 27, having marked thereon a suitable scale 28, over which the end of the pointer 21 moves. Said pointer is controlled by springs 30. Said arc 27 is also formed at its center into a point, as shown at 75 31. Both the pointer 21 and the arc 27 are provided with ink-carriers 32, which travel over a sheet of recording-paper 33. Said recording-paper is caused to be unwound from the roller 34 and wound up on a roller 35, the 80 latter roller being actuated by a spring 36 and moving forward under the action of said spring only as permitted by the motion of a roller 37, which is in frictional contact with the recording-paper 33, and prevents motion 85 thereof except in unison with its own motion. Said latter movement is caused by means of a clock 38, the roller 37 being mounted upon the axle of one of the hands of said clock, preferably the minute-hand. The upward movement of the frame 23 is resisted by means of a spring 39, there being a cord 40 attached at one end to said frame 23 and passed around a pulley 41 and fixedly secured at the other end, said pulley 41 being attached to the upper end 90 of said spring 39 and the lower end of the spring 39 being attached to the board 12. Said frame 23 is guided in its upward movement by the rods 16. The operation of this portion of the apparatus is as follows: When the submerged boat sinks, the pressure in the tubes 3 is increased, thereby increasing the pressure on the diaphragms 5 and 6 and transmitting an increased pressure through the 100

tubes 7, thereby pressing upward the pistons 15 against the action of the spring 39 and raising the frame 23 as a whole, this change in depth being then indicated by 5 means of an upwardly-inclined line marked upon the recording-paper 33, as the latter travels, by means of the inking device 32, attached to the frame. If the boat moves at a uniform depth, this fact will be indicated by 10 the line thus marked being horizontal. If the boat rises, the line will incline downward. When the boat is level, the pressure in the two pistons will balance and the pointer 15 will point exactly to the center of the arc 28, and the line marked by the corresponding inking device 32 will coincide with that indicating the depth of the boat. These two lines will preferably be marked with different-colored inks. Should, however, the boat be 20 inclined, the two lines will not coincide. If the bow of the boat be lower than the stern, the pressure transmitted through the forward tube 7 will be greater than that transmitted through the rear tube 7; and the pressures on 25 the two pistons 15 will differ. If the two diaphragms in each transmitting device were of equal area, then the pressure on the two pistons 15 would not differ however much the boat tilted, for then the pressure on the inner 30 diaphragm 6 being the same as that on the outer diaphragm 5, and the area being the same the pressure per square inch in the tube 7 would be the same as that in the tube 3. This pressure per square inch diminishes in 35 passing up the tube 7 if the latter rises and increases in passing down a descending tube, the pressure added or subtracted being that due to the column of water corresponding to the difference in depth. Thus the pressures 40 in the two tubes 7 at the same depth would be the same; but, as already seen, the two diaphragms 5 and 6 are of different areas, and therefore the pressure in the tube 7 is not the same as that in the tube 3, but is increased in 45 the proportion of, say, two to one if the area of the diaphragm 5 is twice that of the diaphragm 6. In that case, notwithstanding the allowance to be made for the difference in depths between the two ends of the tubes 7, the difference in depths between the bow and the stern of the boat will be indicated by a difference in pressures on the pistons 15. If, however, the bow of the boat be lower than the stern, the pressure on the forward piston will be 55 greater than that on the rear piston and the pointer will point upwardly, so that the red line marked by the inking device 32 of said pointer will be above that indicating the depth. If the bow be higher than the stern, 60 the reverse will be the case. The means will now be explained for causing said recording device to automatically adjust the position of the boat to bring it to a horizontal position. It may not always be desirable that this means 65 should be permitted to operate. The means are thrown into operation when desired by means of a switch 41 in the wire 42.

At the bow and stern of the boat are two water-tanks 43 44, connected by a water-tube 45. Said tanks are connected from their upper portions by means of air-pipes 46 with valve-chambers 47. Said valve-chambers 47 are connected at their lower portions by means of air-pipes 48 49 with a compressed-air chamber 50. From each valve-chamber 75 is also provided in the upper portion an air-vent 51, leading to the atmosphere. In each valve-chamber operates a double valve 52, having upper and lower valve-plates 53 54, connected by a valve-stem 55 and seating 80 themselves upon valve-seats 56 57. The upper and lower ends of said valve-chamber are closed by flexible metallic diaphragms 58 59, with which the stem 55 is connected. When the valve-stem 55 of either valve-controller 85 47 is drawn upward, the upper valve-plate 53 closes upon the upper seat 56, thereby closing the passage between the air-pipe 46 from the corresponding tank to the air-vent 51, and at the same time the lower valve-plate 54 90 rises from its seat 57, thereby opening a passage for compressed air from the compressed-air chamber 50 through the air-pipes 48 49 to said water-tank. The compressed air entering said tank forces the water therefrom through the water-tube 45 to the other tank, the air in the latter escaping, by means of the other air-pipe 46, through the other chamber 47 and air-vent 51. This displacement of the water from one compartment to 100 the other will continue so long as the valve-stem is supported in a raised position. As soon as the force supporting said valve-stem is removed it will be brought down again by means of the resilient force of the metallic 105 diaphragms 58 59, thus closing the valve-plate 54 upon the valve-seat 57 against the passage of compressed air. Moreover, by reason of the area of the lower diaphragm 59 being greater than that of the plate 54 the 110 pressure of the compressed air upon said diaphragm will be greater than its pressure upon said plate, and this will have the effect of holding said plate firmly down to its seat.

I claim—

1. In an apparatus of the character described, the combination, with the shell or body of the submarine boat, of pressure-transmitters, at the ends of the boat, actuated by the external pressure, means for transmitting the pressures therefrom to the same part of the boat, a device reciprocated by both of said pressures and a lever vibrated by the difference of pressures, and moving relatively to said device for the purposes 125 specified.

2. In an apparatus of the character described, the combination, with the shell or body of the submarine boat, of pressure-transmitters at the ends of the boat, actuated by the external pressure, means for transmitting the pressures therefrom to the same part of the boat, a device reciprocated by both of said pressures, a lever vibrated by 130

- the differences of pressures, electric circuits connected to said lever and to two points on said device, said lever being arranged to close one or the other of said circuits by its movement relative to said device, water-tanks at the ends of the boat, and means operated by either circuit when closed for shifting water from one of said tanks to the other, substantially as described.
10. 3. In an apparatus of the character described, the combination with the shell or body of the submarine boat, of an indicator located within said shell immediately of the ends thereof, means for transmitting fluid-pressure from the outside of the boat at the ends thereof to said indicator, and means whereby said pressures so transmitted actuate said indicator to indicate the difference in said pressure, substantially as described.
15. 4. In an apparatus of the character described, the combination with the shell or body of the submarine boat, of an indicator located within said shell immediately of the ends thereof, pressure-transmitting devices at the ends of the boat, and operative connections between said devices and the indicator whereby the latter is operated by said pressures to indicate the difference of pressures, substantially as described.
20. 5. In an apparatus of the character described, the combination with the shell or body of the submarine boat, of an indicator located within said shell immediately of the ends thereof, pressure-transmitting devices at the ends of the boat, tubes from said pressure-transmitting devices to said indicator, and means whereby fluid-pressures in said tubes at the indicator ends operates said indicator, substantially as described.
25. 6. In an apparatus of the character described, the combination with the shell or body of the submarine boat, of an indicator located within said shell immediately of the ends thereof, said indicator comprising guides, pistons moving in said guides, rods carried by said pistons and a pointer operated by said rods, pressure-transmitting devices at the ends of the boat, and tubes from said pressure-transmitting devices connected with said guides, substantially as described.
30. 7. In an apparatus of the character described, the combination with the shell or body of the submarine boat, of a pressure-transmitting device open to the external wa-
55. ter-pressure, a tube leading from said pressure-transmitting device, a guide with which said tube connects, a piston moving in said guide, and a device operated by said piston to indicate said pressure, substantially as described.
60. 8. In an apparatus of the character described, the combination with the shell or body of the submarine boat, of a pressure-transmitting device open to the external water-pressure, a tube leading from said pressure-transmitting device, a guide with which said tube connects, a piston sliding in said guide, a rod carried by said piston, means for advancing a recording-sheet and means carried by said rod for marking said sheet to indicate said pressure, substantially as described.
65. 9. In an apparatus of the character described, the combination with the shell or body of the submarine boat, of pressure-transmitting devices, at the ends of the boat open to the external water-pressure, tubes leading from said devices, guides with which said tubes are connected, pistons moving in said guides, rods carried by said pistons, a 70 pointer with which said rods are pivotally connected, a frame reciprocated by said rods, said frame carrying an arc over which said pointer moves, and means for indicating the extent of the reciprocation of said frame, substantially as described.
75. 10. In an apparatus of the character described, the combination, with the shell or body of the submarine boat, of pressure-transmitting devices at the ends of the boat, 80 an indicator comprising means for advancing a recording-sheet, reciprocating-rods, a frame reciprocated by said rods and moving over said sheet, a pointer vibrated by said rods and moving over said frame, devices carried by said pointer and frame for marking said sheet, and operative connections from pressure-transmitting devices to said rods to reciprocate the same, substantially as described.
85. 100. In witness whereof I have hereunto set my hand in the presence of two subscribing witnesses.

HENRY S. LATHROP.
